UNITED STATES PATENT OFFICE.

JOSEPH KLOPFENSTEIN, OF PARIS, FRANCE.

EQUALIZING ELECTRIC COUPLING.

SPECIFICATION forming part of Letters Patent No. 740,284, dated September 29, 1903.

Application filed August 9, 1902. Serial No. 119,073. (No model.)

To all whom it may concern:

Be it known that I, JOSEPH KLOPFENSTEIN, a citizen of the French Republic, residing at Paris, France, have invented certain new and useful Improvements in Equalizing Electric Couplers, of which the following is a specification.

The present invention has for its object an apparatus called an "equalizing electric coupler," which consists in a construction permitting the employment of lamps of low voltage and high amperage on systems of distribution of electricity of any voltage whatever.

The employment of lamps of low voltage results in a sensible economy in the consumption of electricity transformed into light on account of the very slight loss of caloric by radiation, the surface of their filaments being very much diminished with relation to the volume comparatively with lamps of high voltage.

It is impossible to employ economical lamps on distribution systems the electromotive force of which never gets below one hundred and ten volts, because, as experience has shown, for a medium power of ten to sixteen candles they cannot exceed twenty to thirty volts.

The apparatus of my invention permits, for example, the utilization on distribution systems of one hundred and ten volts of lamps of twenty-two volts. It also renders possible the installation of lamps in simple derivation, as if it was a question of ordinary lamps with voltage equal to that of the sector of distribution. In addition the extinction of one lamp does not entail, as in the single-series system, the extinction of all the other lamps in circuit. This apparatus therefore renders possible and practical the employment of lamps of low voltage on the sector.

My equalizing coupler comprises a box of metal or other material closed on all sides. On the small ends Δ Δ' are fixed two insulated binding-posts B B' to admit the current where the electromotive force is one hundred and ten volts, for example. On the face A are fixed six insulated binding-posts c' c^2 c^3 c^4 c^5 c^6 . On the face A' are fixed twelve other insulated binding-posts d' d^2 e' e^2 e^3 e^4 e^5 e^6 e^7 e^8 e^9 e^{10} . The connections of the different binding-posts between them

are established in the special manner indicated by the schematic drawings annexed hereto. The current arriving at $+B$ goes directly, on the one hand, by g to the binding-post d' , traverses the exterior wiring E F to reenter the coupler by the binding-post d^2 to go directly to the binding-post $-B'$ and return to the line of the sector by that binding-post. The line F therefore permits of the feeding of lamps having a voltage equal to that of the sector. Since the difference of potential between d' and d^2 is exactly that of the sector, it is designed for the feeding of lamps which must generally be lighted and extinguished individually in the installation, lamps for cellars, closets, &c., being intermittently lighted.

A derivation g' , taken on the binding-post $+B$, leads the current at e' to the line H . This current after having traversed the lamps returns to the coupling at e^2 and through the medium of the bridge m' gains by e^3 the line I and reenters at the coupler at e^4 after having traversed the lamps of the line I . In this way the current traverses successively the lines J K L to e^{10} , where it returns to line $-B'$ by the derivation g^2 . Ten lamps of twenty-two volts are placed in derivation on each one of the lines H I J K L , in all fifty lamps. It will be easily understood from the foregoing that the voltage available between e' and e^2 , e^3 , and e^4 , &c., will be equal to that of the sector at $+B$ and $-B'$ divided by the number of the derivations H I J K L . Thus, for example, if the electromotive force of the sector is one hundred and ten volts: $\frac{110}{5} = 22$ volts.

From the foregoing it may also be easily understood that the extinction, whether desired or accidental, of any lamp of one of the lines H I J K L will not entail the extinction of the other lamps. The passage of the current not being interrupted anywhere, there can only result a slight difference of voltage on the line thus thrown out of equilibrium. However, so that this difference of voltage should not be produced and that the extinction of the whole of the lamps of a line becomes possible without producing a disturbance in the other lines derivations n' n^2 n^3 , &c., are taken at e m' m^2 m^3 , &c., which correspond, respectively, to the binding-posts c' c^2 c^3 , &c.,

of the coupler. These binding-posts in their turn are put into relation at points suitably chosen with accumulator-batteries O , each section of which $p' p^2 p^3 p^4 p^5$ is in derivation on $c' c^2 c^3 c^4 c^5 c^6$, and consequently, through the medium of the connections of the coupler, in derivation also on $e' e^2 e^3$, &c. The different sections p of the battery O are in series and the extreme poles, positive and negative, in direct relation with $+B$ and $-B'$ of the coupler. In these conditions the complete extinction of the lamps of the line K , for example, does not entail any disturbance in the other lines, since the section p^4 of the battery O , which corresponds, respectively, to the binding-posts e^7 and e^8 , enters naturally in circuit and furnishes between these binding-posts a counter electromotive force equal to the electromotive force which tends to exist between these binding-posts.

The battery of the accumulators is connected as a reservoir to the line and permits in case of necessity of continuing the lighting for some time if the sector should lack current, which is an appreciable advantage in the lighting of public establishments.

It is possible in the case of lighting an establishment where the number of lamps lighted at one time is sensibly constant to totally dispense with the battery O in using the line F for the individual lamps with intermittent lighting. This deviation $d' d^2$, line F , is created with this object.

The advantage of this apparatus is to permit the employment of economical lamps of low voltage on the sectors distributing at high relative electromotive force without danger of extinguishing all the lamps of an installation as soon as one lamp has accidentally been extinguished, as happens in the mounting in single series, which cannot be practically used. It permits at the same time of an easy installation without any complication in the mounting, this being effected in single derivation on each one of the elementary secondary lines $H I J K L$, &c., as in the installations with ordinary lamps of one hundred and ten volts.

It will thus be seen that the invention provides an arrangement adapted to be connected to a supply-line having a relatively high electromotive force and having a circuit which may include lamps or other translat-

ing devices having a voltage equal to that of the supply and also having a derived circuit composed of a number of sections connected in series, each section including lamps of a relatively low voltage and arranged so that the sum of the voltages of the sections shall equal that of the supply-line. There is also connected in derivation to these sections a secondary battery each section of which is connected between the terminals of two low-voltage sections, and with this arrangement the purpose and object of the invention can be carried out in that the extinction of any one or more of the lamps of high voltage does not affect the low-voltage lamps, and the extinction of one or more of the low-voltage lamps does not result in the extinction of all of them, and the extinction of a group or section of low-voltage lamps does not disturb the others.

What is claimed is—

1. An equalizing-coupler adapted to be connected to a supply-line of relatively high electromotive force, having a circuit including lamps of a voltage equal to that of the supply, and a derived circuit composed of a number of sections, each section including lamps of low voltage, the sum of the voltages of the sections equaling that of the supply-line, and a secondary battery composed of sections, each section connected in derivation between two low-voltage-lamp sections, substantially as described.

2. An equalizing-coupler comprising a case having terminals for the supply-circuit, a series of terminals and lamp-circuits connected thereto, a series of terminals with battery-sections connected thereto, and circuits and connections between said terminals, substantially as described, whereby lamps of different voltage may be supplied from the mains and utilized without interference with each other by connecting battery-sections between the lamp-circuit terminals.

In testimony whereof I have signed my name to this specification in the presence of two subscribing witnesses.

JOSEPH KLOPFENSTEIN.
